UNITED STATES PATENT OFFICE.

DAVID B. PATE AND CHRISTOPHER C. SELF, OF HORNBECK, LOUISIANA.

OIL-BURNING DEVICE.

1,070,722.

Specification of Letters Patent. Patented Aug. 19, 1913.

Application filed September 6, 1912. Serial No. 718,944.

To all whom it may concern:

Be it known that we, DAVID B. PATE and CHRISTOPHER C. SELF, citizens of the United States, residing at Hornbeck, in the parish 5 of Vernon and State of Louisiana, have invented certain new and useful Improvements in Oil-Burning Devices, of which the following is a specification.

This invention relates to oil burning devices.

Our object is to provide an improved oil burning device of simple, inexpensive, safe and durable construction wherein the retort coils will be arranged and packed in an improved 15 manner, enabling the hydrocarbon to be readily subdivided and choked so that it cannot flow too rapidly and its conversion into gas will be assured; a further object being to combine and arrange the 20 spreader, retort and burner in an improved manner.

The invention consists of certain improved features and novel combinations and relations of parts more fully set forth hereinafter.

In the accompanying drawings: Figure 1 is a perspective view; and Fig. 2, a horizontal section through the retort, showing the packing and wires therein and illustrating a supplemental support for the spreader.

The burner 1 may be of any preferred shape and is constructed of a single piece of pipe closed by caps or nipples 2 at its 35 ends and provided with openings in its upper face. A casting could be substituted and the caps dispensed with. Cups or special burners 1^a may be employed, if desired. Joined to the burner by a coupling 30 40 is a feed pipe 4.

The retort, which may be circular, rectangular, or of any preferred shape, consists of pipe sections 6 coupled to and in communication with the pipe section 4 at 45 one end and connected to an ordinary feed pipe 7 leading to any suitable source of hydrocarbon supply and provided with a needle valve 8, whereby the flow of the hydrocarbon to the pipe 7 and thence to retort pipes 6 for gasification, may be controlled.

In the pipe elbows 9 we provide a packing of asbestos 10. Fine wire, suitably coiled or convoluted may be substituted for the asbestos. In the pipes 6 we provide longitudinally extending pieces of wire which may be spread, convoluted, crimped, or otherwise formed, said wires being shown at 11, 12 and 13, respectively. The packing in the elbows 9 and the wires in the retort 55 pipes 6 choke the hydrocarbon and prevent its too rapid passage in said elbows and pipes, beside tending to break up the hydrocarbon, thereby insuring more perfect gasification of the hydrocarbon, the latter passing as a gas down pipe 4 into the burner 1. A spreader 5 is supported by a stem 5^a from burner 1 and may be additionally supported by metal bands or hooks 5^b.

To start the burner, a small supply of 70 hydrocarbon may be ignited on the spreader 5 to initially heat the retort pipes. The spreader 5 diverts the flame around all parts of the retort. The needle valve 8 enables any desired regulation of the supply 75 of hydrocarbon and also insures against any sudden flow of hydrocarbon to the burner with dangerous consequences should the burner be tampered with by children or those not understanding its working.

Having thus described our invention, what we claim is new and desire to secure by Letters Patent, is:—

In an oil burning device, the combination 85 with a retort consisting of horizontally disposed pipe sections and elbows connecting them, of packing in the elbows, wires extending lengthwise within and throughout the pipe sections, a burner disposed below and communicating with the retort, and a 90 spreader located below the retort and above the burner, said spreader being supported by the burner.

In testimony whereof, we hereunto affix our signatures in presence of two witnesses. 95

DAVID B. PATE.
CHRISTOPHER C. SELF.
